United States Patent Office

Des. 232,338

Patented Aug. 13, 1974

232,338

COLANDER

Robert Daenen, Erembodegem, Belgium, assignor to Dart
Industries, Inc., Los Angeles, Calif.

Filed Apr. 23, 1973, Ser. No. 353,284

Term of patent 14 years

Int. Cl. D7—04

U.S. CL. D7—47

FIG. 1

FIG. 2

FIG. 3

FIG. 4

FIG. 1 is a front or rear elevational view of a colander showing my new design;

FIG. 2 is a side elevational view thereof;

FIG. 3 is a top plan view thereof; and

FIG. 4 is a bottom plan view thereof.

I claim:

The ornamental design for a colander, substantially as shown.
